CLAIM

I claim the ornamental design for a double-walled glass with 4 opposing dimples, as shown and described.

DESCRIPTION

FIG. 1 is a perspective view of a double-walled glass with 4 opposing dimples, showing my new design;

FIG. 2 is a front elevational view thereof, the rear elevational view being a mirror image thereof;

FIG. 3 is a top plan view thereof;

FIG. 4 is a bottom plan view thereof; and,

FIG. 5 is a cross-sectional view thereof, taken along line 5-5 of FIG. 4.
